UNITED STATES PATENT OFFICE.

ETHAN I. DODDS, OF PULLMAN, ILLINOIS, ASSIGNOR TO THE PULLMAN COMPANY, OF CHICAGO, ILLINOIS, A CORPORATION OF ILLINOIS.

MINING-CAR.

No. 834,003.

Specification of Letters Patent.

Patented Oct. 23, 1906.

Application filed June 24, 1905.—Serial No. 266,810.

To all whom it may concern:

Be it known that I, ETHAN I. DODDS, a citizen of the United States, residing at Pullman, in the county of Cook and State of Illinois, have invented certain new and useful Improvements in Mining-Cars, of which the following is a specification.

My invention relates to cars of that type used in coal-mines, stone-quarries, cement-works, &c.

Cars of this class are subjected to rough treatment and quickly become broken and worn out unless carefully handled, the expense of repairing the ordinary wooden cars used in mines, &c., amounting to about twenty-five per cent. per year of the total value of the cars.

The object of my invention is to produce a metal car of this class which shall be simple and economical to construct and tough and durable in use.

To this end my improved car is constructed throughout of standard rolled sections and metal plates rigidly united and so disposed as to prevent the transmission of longitudinal shocks through the sides of the car.

My invention also comprehends a novel means for locking the end door of the car.

A car constructed in accordance with my invention is illustrated in the accompanying drawings, wherein—

Figure 1 is a plan view of the car. Fig. 2 is a side elevation of the same. Fig. 3 is an end elevation showing the permanently-closed end, and Fig. 4 is a short section taken on the lines 4 4 of Fig. 1.

The car as herein illustrated has vertical front and rear walls, one of which is constituted by a hinged door, and sloping or flaring side walls, although such particular conformation of the walls is not of the essence of the invention. Referring to the drawings, 5 may designate the bottom wall of the car; 6, the inclined side walls; 7, the permanent end wall, and 8 a hinged door constituting the other end wall. These members are all made of comparatively light metal plates reinforced, as hereinafter described.

9 designates a heavy steel or iron bar riveted to the bottom wall 5 coincident with the major axis thereof and extending from end to end of the car and projecting beyond the ends for a limited distance, as shown in Fig. 1. This bar performs the double function of a

floor-stiffener and a draft-bar. The side and bottom walls and the end wall 7 are united at their meeting edges by internal angle-bars 10, rigidly bolted thereto, and the upper margins of the side walls 6 and end wall 7 are reinforced by angles 11, extending the entire length thereof. The vertical corners of the car at the closed end are united and reinforced by means of channels 12, Fig. 3, that are brought to the required shape by bending the web to rectangular form to fit the corners, as clearly shown in plan view, Fig. 1. The sides of the car are reinforced against lateral pressure by means of side stakes 13, which are formed, preferably, by a flanged rolled member cut on the bias through its web. The lower ends of the side stakes 13 are secured to an angular member 14, that is disposed transversely of the car beneath the floor. The ends of the side walls adjacent to the door are reinforced by vertical rolled sections 15 of the T shape, with the web cut on the bias similarly to the side stakes 13.

To further reinforce the car against longitudinal strains and thrusts an angle-bar, (denoted by 16,) bent into substantially semicircular form, is provided at each end of the car. This bar is secured at its central point to the projecting end of the longitudinal bar 9, while its ends are riveted to the ends of the angles 10. The members 16 thus perform the office of bumpers, distributing the longitudinal shocks and strains through both the central longitudinal bar 9 and the parallel angles 10 on either side thereof.

To the door 8 are riveted hinge members 17, that extend, preferably, the full height of the door for purposes of lateral reinforcement, as shown in Fig. 4, said hinge members being hung at their upper ends on a horizontal hinge-pintle 18, mounted at its ends in brackets 19, secured to the upper ends of the side walls.

To the upper face of the bar 9 at the closed end of the car is secured a coupling-hook 20, and to the opposite end is secured a combined hook and staple 21, adapted to be engaged by a section of chain 22 for coupling purposes.

My invention also comprehends a simple and easily-manipulated form of door-lock, the same comprising a rod or bar 23, mounted to oscillate in bearings 24, secured to the front face of the door at its lower end, said

rod having an offset portion 23^a formed at its center between the bearings 24 and having also downwardly-bent ends 23^b overlying the sides of the buffers 16. This rod is so disposed that when thrown into locking position by swinging downwardly one or both ends 23^b the central offset 23^a engages the rear end of the coupler-hook 21, which latter forms a stop preventing the opening of the door. In order to release the door when the load is discharged, as by raising the closed end of the car, it is necessary only to raise one of the depending arms 23^b, which can be easily done by a mere kick of the operator, which frees the lower end of the door and allows it to swing open.

This patent is intended to embrace only so much of the disclosure made herein as is covered by the claims.

20 I claim—

1. A metal car of the class described comprising a horizontal bottom wall, a vertical end wall, inclined side walls, and a vertical swinging door closing one end, all of said parts being made of metal plates united and reinforced by rolled beams riveted thereto, substantially as described.

2. A car of the class described having in combination a draft-bar disposed coincident with the major axis of the car and having its ends projecting beyond the car-body, and buffers in the form of bent angles united to the ends of said draft-bar, substantially as described.

3. A metal car of the class described having, in combination with a body formed of metal plates united and reinforced by rolled beams, a draft-bar disposed coincident with the major axis of the car and having its ends projecting beyond the ends of the car-body, and buffers in the form of bent angles united to the ends of said draft-bar, substantially as described.

4. A metal car of the class described comprising a body formed of metal plates united

at their meeting edges by angle-irons, in combination with a draft-bar disposed coincident with the major axis of the car and projecting at its ends beyond the end walls of the car, and buffers in the form of bent angles secured 50 at their centers to the ends of said draft-bar and connected at their ends to the ends of the angles uniting the bottom and side walls, substantially as described.

5. The combination with a metal car-body 55 of the class described, of a hinged door closing one end of said car-body, said door being swung from its upper end, a locking-bar having an offset portion journaled on said door transversely of the car, and a stop 60 adapted to be engaged by the offset portion of said locking-bar to maintain the door closed, substantially as described.

6. The combination with a metal car-body having one end thereof formed by a door 65 hinged at its upper end, of a locking-bar pivotally mounted upon and parallel with the lower free margin of said door, said bar having an intermediate offset portion and a depending arm at one end, and a stop adapted 70 to be engaged and disengaged by the offset portion of said bar to lock and release the door, substantially as described.

7. The combination with a metal car-body 75 of the class described, having one end thereof formed by a door hinged at its upper margin, of a draft-bar extending longitudinally of the car and projecting beyond the ends of the latter, coupling-hooks secured upon the ends of said bar, and a centrally-offset locking-bar 80 pivoted upon and coincident with the lower margin of said door, the offset portion of said bar engaging the rear end of one of said coupling-hooks to thereby lock the door in closed position, substantially as described.

ETHAN I. DODDS.
